UNITED STATES PATENT OFFICE.

GEORGE M. D. RILEY, OF SAVANNAH, GEORGIA.

LOCOMOTIVE HEAD-LIGHT.

SPECIFICATION forming part of Letters Patent No. 331,654, dated December 1, 1885.

Application filed November 19, 1884. Serial No. 148,314. (No model.)

To all whom it may concern:

Be it known that I, GEORGE M. D. RILEY, of Savannah, in the county of Chatham and State of Georgia, have invented certain new and useful Improvements in Locomotive Head-Lights, of which the following is a specification, reference being had to the accompanying drawings, and to the letters of reference marked thereon.

10 The object of this invention is to provide the head-light with means for holding an ordinary hand lamp or lantern in the event of an accident occurring to the head-light lamp, or to the glass disk in front of the reflector, or 15 other accident, by which the value of the head-light might be impaired.

The invention consists, broadly, in attaching to the head-light a device capable of holding an ordinary lamp or lantern in such position as that the light thereof shall practically 20 take the place of the light of the proper head-light lamp.

In the drawings, Figure 1 is a vertical longitudinal section of a head-light box and reflector having my improvement, in its preferred form, attached thereto. Fig. 2 is a front view of the improvement, and Fig. 3 a plan.

Similar letters of reference indicate similar 30 parts in the respective figures.

A is the head-light box or case, and B the reflector. C is a ring made of tin, sheet-brass, or other metal. The interior diameter of the ring within the flange *a* is sufficient to receive 35 the lower portion of an ordinary hand-lantern, C'. The ring C is supported by means of two brackets or standards, *b*, which are secured to the front of the head-light case, or to any other suitable part of the head-light or reflector.

40 The ring is provided with a spring, *c*, one end of which is secured to the ring, as shown at *d*, the other end being free, as shown at *f*. The free end of the spring is adapted to be forced

in against the hand-lantern C' by means of a set-screw, *g*, which passes through the side of 45 the ring, and which is threaded to receive it. On the inner side of the ring are arranged pins or lugs *h*, designed to fit over the edge of the lantern, so as to keep it from rising or falling when the engine is in motion.

It has been found heretofore that where such an accident occurs as is above referred to, and a lantern is hung upon the rail, the light produced has been inadequate for the purposes required, and that it has been very difficult for 55 an engineer upon another train to locate the train carrying the lamp upon the rail. Serious accidents are therefore liable, on account of the inability of the engineer to measure the distance between his train and that carrying 60 the lamp on the rail.

My invention has been found to serve all the purposes of the ordinary head-light lamp, and to take its place, temporarily, with satisfactory results.

Having described my invention, I claim—

1. In combination with a locomotive head-light, a clamping-ring secured to the head-light case or reflector and extending upward within the reflector and adapted to receive and 7c clamp the lower end of an ordinary lamp or lantern, substantially as set forth.

2. In combination with a locomotive head-light, a ring or clamp secured to the head-light case or reflector and extending upward within the reflector provided with lamp or lantern clamping devices and means for preventing vertical movement of the lamp or lantern, substantially as set forth.

In testimony whereof I have hereunto set 80 my hand and seal.

G. M. D. RILEY. [L. S.]
